CURTAIN ROD

Filed Nov. 6, 1931

UNITED STATES PATENT OFFICE

ISIDOR WEINBERG, OF BROOKLYN, NEW YORK

CURTAIN ROD

Application filed November 6, 1931. Serial No. 573,476.

This invention relates to improvements in curtain fixtures particularly in fixtures in which the left and right hand parts of a curtain suspended from the fixture by means of 5 slides or runners, are drawn together or moved apart, by the operation of a pull cord, and it is the principal object of my invention to provide a fixture the telescoping members of which carry master slides attached to the 10 pull cord which at all times are centrally located to said members which are substantially U-shaped in cross-section and have a rounded apex while the lower ends of the U-shanks are inwardly and upwardly bent 15 to form guides in which the members are guided during their telescoping displacement to one another.

Another object of my invention is the provision of double duty brackets at the outer 20 ends of the end members of the fixture to allow the attachment of the fixture by one part of the double duty bracket either between the inner oppositely disposed faces of a window sash or the like, or to permit the attachment 25 of the fixture by means of the other part of said double duty bracket to the side faces of a window sash or the like.

Still another object of my invention is the provision of a curtain fixture the pull cord 30 of which is guided over suitably arranged inner sheaves in such a manner as to allow the pulling apart of the curtain parts by a pull at one end of the cord or the drawing together 35 of the parts of the curtain by a pull at the other cord end.

A further object of my invention is the provision of a plurality of slides or runners from 40 which the parts of a curtain are suspended including centrally located master slides adapted to be pulled apart or drawn together on the central or main member by a pull on the cord and sliding on a seat formed by the inwardly and upwardly bent ends of the fixture members.

45 A still further object of my invention is

the provision of a curtain fixture the draw or pull cord of which is reentrantly guided over sheaves and secured intermediate its ends to the centrally located slides for the curtain, and a fixture which is comparatively 50 simple and inexpensive in construction, yet durable and highly efficient in operation.

Other objects and advantages of my invention will become more fully known as the description thereof proceeds, and will then be 55 specifically defined in the appended claims.

In the accompanying drawing forming a material part of this disclosure:

Fig. 1 is a top plan view of an extension curtain rod constructed according to my invention.

Fig. 2 is a side elevation thereof.

Fig. 3 is a longitudinal section through the fixture on an enlarged scale.

Fig. 4 is a cross-section on line 4-4 of 65 Figure 3.

Fig. 5 is a cross-section on line 5-5 of Figure 3.

Fig. 6 is a vertical transverse section on line 6-6 of Figure 3, on an enlarged scale. 70

Fig. 7 is a perspective view of a double end bracket.

Fig. 8 is a diagrammatic detail view of the draw cord arrangement.

As illustrated, the curtain rod or fixture 75 according to my invention consists of a central or main section 10 and two sections 11 and 12 telescoping endwise into said main section.

Each section consists of a body part substantially 80 U-shaped in cross section having a rounded apex and parallel downwardly directed spaced shanks the lower ends of which are inwardly and upwardly bent, as indicated at 13 and 14, the bends of the main section forming a guide for the bends of the end sections slidably held therein during the telescoping operation and forming a seat for the upper bar or head 15 of the slides 16 and master slides 16, 16', having each a web 90

17 connecting the head to the foot of the slides 16" and master slides 16, 16', bent angularly to form a depending member 18 perforated at 19 to allow the passage of the fastening or suspending means of the curtain.

The apex of member 12 is slotted, as at 20, to permit the telescoping of member 12 into the main section.

The outer ends of the end sections 11 and 12 10 are equipped with double duty brackets, one part of each bracket composed of a plate 23 and end plate 24 angularly disposed thereto and perforated, as at 25, to allow the passage of the fastening means by which the fixture 15 is to be secured to the inner faces of a window frame, while bracket 23 integral with plate 24 and angularly disposed thereto has perforation 26 to allow the passage of fastening means securing the bracket to the end member 12, and perforation 21 from which the outer ends of the curtain are suspended.

Integrally formed with plate 24 and angularly disposed thereto is the other part of the double duty bracket composed of a substantially 25 U-shaped body part or plate 27 connected by means of a web 28' to plate 23 and having the upper and lower ends of the U-shanks angularly bent to form upper and lower flanges 28, 29, provided with openings 30, 31, allowing the passage of the fastening means to secure the bracket member 27 to the outer faces of a window-frame.

A sheave or small pulley wheel 32 is rotatably mounted on a pin 33 near the outer end 35 of the right hand section between the walls of member 11 and one end of a pull cord 34 is guided over the sheave and has secured thereto master slide 16 by means of a screw 35. The cord 34 is then guided over a sheave 36 40 secured by means of a pin 37 to a U-plate or yoke 38 attached to the apex of member 10 by means of screw 22.

The cord is then reentrantly guided over a pulley or sheave 39 on pin 40 near the inner end of the left hand end section of the rod and from this sheave cord 34 is guided over a sheave 41 on pin 42 near the outer end of the left hand section between the walls of member 12. From sheave 41 cord 34 is guided over a small roller 43 on pin 44 in a member 45 secured in member 12. At a distance from roller 43 cord 34 is attached by means of screw 44 to master slide 16' and finally guided over a pulley or sheave 46 on pin 47 inward of and somewhat below sheave 32 and has its end 48 suspended for the attachment of a suitable weight. A similar weight is attached to end 34 of the cord.

In operation, the fixture is adjusted to its proper length by the telescopic adjustment of the end members relatively to the main member, and is then either attached endwise to the inner faces of the window sash by suitable fastening means passed through openings 25 in plate 24 or by means of screws or the like

passed through the openings 30, 31, of bracket member 27, if the fixture is to be attached to the front face of a window sash or the like. In adjusting the fixture to a given length, the end members should each be lengthened or shortened equally relative to the main member. It will be apparent, that by such adjustment, the master slides governing the movements of the curtain, will at all times be centrally located on the rod, due to the prescribed arrangement of sheaves, provided by the present invention.

The curtain is suspended from the slides 16" and master slides 16, 16', by hooks, pins, or the like, passed through the openings 19. If now a pull is exerted on end 34 of the pull cord, the master slides 16, 16', from which the inner ends of the curtain are suspended will distance the ends of the curtain to any desired degree to provide an opening while a pull on end 48 will approach the curtain ends towards the center so as to overlap and close the curtain and close the opening.

It will be understood that I have described and shown the preferred form of my device only as one example of the many possible ways to practically construct the same, and that I may make such changes in the general arrangement thereof and in the construction of its minor details as come within the scope 95 of the appended claims without departure from the spirit of my invention and the principles involved.

Having thus described my invention, what I claim as new and desire to secure by Letters 100 Patent is:

1. A curtain rod, comprising a hollow central member and a pair of hollow end members telescoping endwise into said central member, a sheave mounted at each end within one of said end members, a pair of sheaves mounted at the outer end within the other of said end members, a sheave mounted at one end within said central member, a pull cord extending through said rod and guided over said sheaves, curtain hanger slides mounted to slide within said rod members, and means for connecting said pull cord to the innermost two slides.

2. A curtain rod comprising a hollow central member and a pair of hollow end members telescoping endwise into said central member, a sheave mounted at each end within one of said end members, a pair of sheaves mounted at the outer end within the other of said end members, a sheave mounted at one end within said central member, a pull cord extending through said rod and guided over said sheaves, curtain hanger slides mounted to slide within said members, the innermost two slides being connected to said pull cord intermediate its ends.

3. A curtain rod comprising a hollow central member and a pair of hollow end members telescoping endwise into said central

member, a sheave mounted at each end within one of said end members, a pair of sheaves mounted at the outer end within the other of said end members, a sheave mounted at one 5 end within said central member, a plurality of curtain hanger slides mounted to slide within said members, and a pull cord extending through said rod to which are secured the two innermost slides intermediate the ends 10 thereof, said pull cord guided over one of said pair of sheaves within said end member to one of the innermost slides, over the sheave in the central member, over the inner sheave of the other end member to the outer sheave 15 in said end member, reentrantly to a guide and to the other of said innermost slides and over the other sheave in the first named end member.

4. In a curtain rod substantially as claimed 20 in claim 2, a pull cord guided over one of said pair of sheaves within said end member to one of the innermost slides, over the sheave in the central member, over the inner sheave of the other end member to the outer sheave 25 in said end member, reentrantly to a guide and to the other of said innermost slides and over the other sheave in the first named end member, the free ends of said pull cord depending from said rod and adapted to draw 30 together curtains suspended from the slides by a pull at one end of said cord and to pull apart said curtains by a pull at the other end of said cord.

5. A curtain rod comprising a hollow central member and a pair of hollow end members telescoping endwise into said central member, each of said members being substantially U-shaped in cross section and having 35 rounded apices, and inwardly and upwardly bent spaced parallel ends forming a longitudinally extending inner seat, a plurality of curtain hanger slides mounted to slide on said seat, a sheave mounted at each end within one of said end members, a pair of sheaves 40 mounted at the outer end within the other of said end members, a sheave mounted at one end within said central member, a pull cord extending through said rod and guided over said sheaves, and means for connecting said 45 pull cord to the innermost two slides.

6. A curtain rod comprising a hollow central member and a pair of hollow end members telescoping endwise into said central member, a sheave mounted at each end with- 50 in one of said end members, a pair of sheaves mounted at the outer end within the other of said end members, a sheave mounted at one end within said central member, a longitudinally extending seat formed within said 55 members, a plurality of curtain hanger slides mounted to slide on said seat, a pull cord extending through said rod and guided over said sheaves, means for connecting the two innermost slides to said pull cord intermediate the ends thereof, the position of said two 60

innermost slides remaining undisplaced when the two end members are telescoped an equal distance relative to the central member.

7. A curtain rod comprising a hollow central member and a pair of hollow end members telescoping endwise into said central member, each of said members being substantially U-shaped in cross-section and having rounded apices and, inwardly bent ends in spaced parallel relation to each other forming a longitudinally extending inner seat, one of said end members having a longitudinal slot in its apex, a sheave mounted at each end within said end member, a pair of sheaves mounted at the outer end within the other of said end members, a sheave mounted at one end within said central member, means for connecting said sheave to said central member between the sheaves in the first named end member, a plurality of curtain hanger slides mounted to slide on said seat, a pull cord extending through said rod and guided over said sheaves, and means for connecting the innermost two slides to said pull 70 75 80 85 90 95 100 105 110 115 120 125 130

cord intermediate the ends thereof.

8. A curtain rod comprising a hollow central member and a pair of hollow end members telescoping endwise into said central member, each of said members being substantially U-shaped in cross-section and having rounded apices and inwardly bent ends in spaced parallel relation to each other, forming a longitudinally extending inner seat, one of said end members having a longitudinal slot in its apex, a yoke within said slotted end member attached to one end of said central member by means extending through said slot, a sheave mounted at each end within said end member, a pair of sheaves mounted at the outer end within the other of said end members, a sheave mounted in said yoke intermediate the sheaves in the first named end member, a plurality of curtain hanger slides mounted to slide on said seat, a pull cord extending through said rod and guided over said sheaves having its free ends depending from one end of said rod and adapted to draw together curtains suspended from the slides by a pull at one end of said 100 105 110 115 120 125 130

cord, and to draw apart said curtains by a pull at the other end of said cord.

9. A curtain rod comprising a hollow central member and a pair of hollow end members telescoping endwise into said central member, each of said members being substantially U-shaped in cross-section and having rounded apices and inwardly bent ends in spaced parallel relation to each other forming a longitudinally extending inner seat, a sheave mounted at each end within one of said end members, a pair of sheaves mounted at the outer end within the other of said end members, a sheave mounted at one end within said central member inter-

mediate the sheaves in the first named end member, a plurality of curtain hanger slides mounted to slide on said seat, a pull cord extending through said rod and guided over said sheaves having its free ends depending from one end of said rod and being connected to the innermost two slides intermediate its ends, the position of said two innermost slides remaining undisplaced when the two end members are telescoped equally relative to the central member.

In testimony whereof, I have signed my name to this specification this 17 day of October, 1931.

ISIDOR WEINBERG.
